UNITED STATES PATENT OFFICE.

CHARLES T. SEGAR, OF UTICA, NEW YORK.

FOLDING BED OR COT.

SPECIFICATION forming part of Letters Patent No. 316,298, dated April 21, 1885.

Application filed June 24, 1884. (No model.)

To all whom it may concern:

Be it known that I, CHAS. T. SEGAR, a citizen of the United States, residing at Utica, in the county of Oneida and State of New York, have invented certain new and useful Improvements in Folding Beds or Cots; and I do declare the following to be a full, clear, and exact description of the invention, such as will enable others skilled in the art to which it applies to make and use the same, reference being had to the accompanying drawings, and to letters or figures of reference marked thereon, which form a part of this specification.

Figure 1 of the drawings is a side view of my device. Fig. 2 is a bottom view of the same. Fig. 3 is also a bottom view folded, and Fig. 4 is an end view.

This invention has relation to folding cots; and it consists in the construction and novel arrangement of devices, as hereinafter set forth, and pointed out in the appended claims.

In the accompanying drawings, the letters A A designate the side rails of the cot, to which the webbing or fabric B is attached. C C are the legs, which are pivoted to the rails near the ends thereof, the pivots D extending transversely, so that when the legs are folded they will lie alongside the rails.

Each pair of legs is connected by a cross-bar lever-frame extending transversely, and consisting of the cross-levers E, pivoted to the lower portions of the legs, as at F, and together at the point of intersection G. Extensions H of these levers beyond the point of intersection are pivoted to the locking-arms K, the outer ends of which are pivoted to the upper portions of the legs, as shown at L. The inner extensions, N, of these arms, which are prolonged beyond the pivots P, are of proper length to engage the upper edges of the cross-levers E just above the point of intersection G when the legs are the full distance apart from each other. In this position the pivot-points P are below the level of the pivot-points L, and the legs are locked apart in stretched relation.

S S indicate oblique braces, which are by their lower ends connected to the middle portions of the cross-levers E and by their upper ends to pivot-bearings T of the side rails,

said bearings being nearer the ends of the rails than the pivots which connect the legs to said rails. When the side rails are stretched apart, these braces operate to draw the cross-lever connection and the legs into upright position, and when the rails are pushed toward each other the braces S cause the legs and their connecting-levers and locking-bars to be folded into the plane of the side rails.

In operating this cot when folded, the legs are first pulled out at right angles to the rails, this operation causing the side rails to recede from each other through the action of the oblique braces S. Then by pulling the legs apart by their lower ends the locking-bars K are caused to spring downward into engagement with the cross-levers, throwing the latter into locked position, so that the legs will be held firm and steady. In closing the cot the operation is reversed, the legs being first pushed toward each other to loosen the locking-bars, after which the rails are pushed together.

V represents the bolster-strip, the ends of which are connected to wires w, to which are pivoted the upper ends of the parallel spring-arms Z—two on each side—the lower ends of which are pivoted to bearings a, secured to the rails near the head of the cot-frame. The pivotal portion of the inner spring-arm Z on each side, after passing through its bearing a terminates in a short crank-arm, b, which is connected to the adjacent leg C by a link, d. When the leg C is folded down, it draws the crank-arm b downward, and at the same time the arms Z are caused by said crank-arm to be folded down upon the sides of the cot-frame, and when the legs are unfolded the arms Z are raised and the bolster-strip is stretched and held in position for use.

Having described this position, what I claim, and desire to secure by Letters Patent, is—

1. The combination, with the side rails of a cot, and the legs pivoted thereto, of the cross-levers E, pivoted to each other, to the locking-arms K, and to the lower portions of opposite legs, and the locking-arms K pivoted to the upper portions of said legs and to the extensions of said cross-levers, substantially as specified.

2. The combination, with the side rails and pivoted legs of a cot, of the cross-levers extended beyond their intersection, the locking-arms pivoted to the extensions thereof and 5 pivoted to the legs, and the brace-rods connecting the cross-levers to the side rails, substantially as specified.

In testimony whereof I affix my signature in presence of two witnesses.

CHARLES T. SEGAR.
